MEANS FOR FEEDING A CONTINUOUSLY
UNIFORM QUANTITY OF FLUIDSJohannes van Dartelen, Vlissingen, Netherlands,
assignor to Deutsche Waffen- und Munitions-
fabriken A.-G., Berlin-Charlottenburg, Ger-
many, a joint-stock company of GermanyApplication July 6, 1937, Serial No. 152,203
In Austria July 9, 1936

3 Claims. (Cl. 103—11)

This invention relates to a device, or in general to means for feeding continuously uniform quantities especially of liquids but also of vapors or gas and of spinning solutions for the manufacture of artificial silk, artificial fibres or the like, by combining a feeding device with a discharge regulating device. In connection with this arrangement the quantity fed by the feeding device should be greater than the quantity taken up and fed by the regulating device. Furthermore, in the device a diaphragm responsive to pressure should be inserted.

The main feature of the invention consists in the fact that two or more feeding devices are arranged before the device regulating the quantity. These feeding devices may be arranged as geared pumps one behind the other, that is in line, or one beneath the other, that is in parallel. The feeding elements of one pump are arranged so with respect the feeding elements of the other as to give a phase-displacement.

Devices are known which tend to give a uniform and equal feeding of liquids even in respect of a changing resistance within the discharging tubes. However, with these known devices the desired effect of a completely uniform feeding even in the case of an elevated pressure of resistance within the discharging pipes cannot be attained, because these known devices consist of only two rotary—or geared—pumps arranged in line and driven in such a manner that the feeding effect of the first pump is greater than the feeding effect of the second pump arranged behind the first and fed by the same. The rearward flow of the fed liquid in connection with changing pressures and the faults created thereby cannot be avoided with these known devices, because they contain a single feeding device only in connection with a pressure regulating device, by which only the feeding to a second device producing the final feeding may be regulated.

Furthermore, these known devices even with some constructional changes cannot be used in practice because they can be inserted into a great number of existing machines, especially into the machine for the manufacture of artificial silk, only if these machines are subjected to great changes, which cannot be made without stopping these machines and the plants, because the devices do not agree with the "bridges" of the spinning machines for artificial silk. In connection with these machines the continuously uniform feeding is of greatest importance, because the pressures in the discharging tubes sometimes

climb up to such a height that a uniform feeding cannot be maintained.

Up to now there has not become known a single device, which would ensure a uniform feeding, that is with a pressure of 30-40 atmospheres in the feeding and the discharging elements forming the transporting organs of the pump. This great disadvantage causes heavy faults in the product, e. g., when manufacturing artificial silk so that this product becomes useless.

The demand to feed a completely uniform and continuous quantity of liquid even within the smallest time-intervals cannot be fulfilled with a single feeding device, and consequently the invention proposes a device in which the feeding of the liquid or the like to the regulating device will be effected by means of two or more geared pumps which in the best manner may be arranged in line, but which can be arranged in parallel as well.

The position of the feeding teeth of the pairs of gear wheels of the two or more feeding devices will be such that the teeth are offset with respect to the feeding phase so that the number of periods may be increased in a simple manner. If for instance, two pumps are arranged one behind the other the number of periods will be nearly doubled, and it will be increased further in connection with a still greater number of feeding pumps. At the same time the periods are diminished with respect to the difference of fluctuation thus ensuring within smallest intervals of time a uniform and shockless feeding of liquid even if the pressure difference within the feeding and discharging tubes changes, that is, rises.

In order to cut off the discharging pipe behind the regulating device and in order to thus avoid loss of packing or the like in view of wear of the feeding teeth of the regulating device according to the invention a cut-off device may be used consisting of a diaphragm entering into action at once if the regulating device transports a small quantity. This sudden entering into action may be attained according to the invention (in contrast with known constructions) by a completely symmetrical arrangement of this diaphragm with respect to the feeding and discharging pipes. A further safety valve may be provided, for instance as a small frangible plate which will break in a known manner if a certain maximum pressure is reached, and thus serving as a safety valve protecting the device from higher pressures than the desired pressure admitted by the construction.

According to the invention also this safety de-

vice is inserted into the stream of the discharged liquid, and thus dead spaces, as they appear in connection with other constructions, are completely avoided.

5 To more clearly describe the present invention the annexed drawing may serve in connection with the following description. The drawing shows an example.

10 Fig. 1 is a longitudinal section of a feeding and regulating device according to the invention.

Fig. 2 is a longitudinal section taken at right angles to the section according to Fig. 1.

Fig. 3 is a fragmentary view of the feeding teeth of the feeding pumps.

15 In order to render the illustrations perfectly clear a number of arrows are indicated in Figs. 1 and 2 to show the feeding direction of the fluid.

The fluid (liquid, vapor, gas or the like) is fed with a certain pressure created by air-pressure 20 or a compressing device (not shown) to the channel 1 (Fig. 1). This channel 1 is in communication with the suction channel 2 of the feeding pumps 3, and furthermore with the opening 4 of the right chamber 5 of a chamber 6 which is

25 divided by means of an elastic diaphragm 8 into a right chamber 5 and a left chamber 7. The elastic diaphragm may consist of rubber or a thin plate of steel clamped between the plates 9 and 10 forming a part of the housing of the 30 device according to the invention.

By means of an opening 11 the right chamber 5 of the chamber 6 is connected to the channel 12 which is in communication with the feeding devices 3 and an opening 13 connected to the 35 suction channel 14 (Fig. 2) which latter connects the feeding devices and the regulating device 15. The pressure channel 16 of this regulating device 15 opens at 17 into the left chamber 7 of the room or chamber 6, and connected to this chamber 7 is the opening 18 which is in communication with the discharging channel 19. Into this channel 19 a safety valve 20 is inserted constituted by a frangible plate covering an opening of this channel and being capable of breaking, if 45 a certain maximum pressure will be exceeded.

The feeding device 3 feeds a greater quantity of fluid than that taken up by the regulating device 15 arranged behind the feeding device 3. This feeding device 3 consists of at least two 50 pumps, but according to the invention a greater number of these pumps may be used as well.

The operation of the device is as follows:

Under the action of the pressure created by an outer pressure source (not shown) the fluid enters through the channel 2 into the feeding pumps 3, by means of which it is brought through the channel 12 and the opening 11 into the right chamber 5 and further through the opening 13 into the channel 14 of the regulating device. 60 In view of the pressure created by the feeding pumps 3 the diaphragm 8 will be bent to the left thus completely or partially closing the discharging pipe 18. The surplus of the fed fluid which will not be taken up by the regulating device 15 flows to the right chamber 5 and back to the channel 1 through the opening 4.

The regulating device 15 feeds the fluid through the channel 16 and the opening 17 into the left chamber 7. In the case of equal pressures in the right and the left chambers 5 and 7 the opening 18 will be free, so that the fluid to be fed flows through the channel 19 to the device which feeds the fluid to the place of use. If the counter-pressure within the channel 19 becomes too great the closing pressure, at which

the opening 4 will be closed, will be determined by this counter-pressure and the opening 4 will be free only if this counter-pressure will be overcome by the pressure created by the feeding pumps. Thus it can be attained that the pressures within the suction channel and within the discharging channel 16 are always equal, so that the feeding effect will be uniform and will always remain independent of any wear of the feeding teeth or of any changing pressure, as 10 may arise in practice by clogging of the spinning holes, by an elevated viscosity or by other reasons.

As may be clearly seen from the drawing the channel openings 4, 11, 13, 17 and 18 are arranged 15 symmetrically with respect to the divided chamber 6 so that faults in the working of the regulating diaphragm 8, in view of a difference of pressure, may be avoided as in similar known arrangements. If a pressure difference exists this diaphragm acts to one side as a throttling device and to the other side it increases the passage to greater quantities of fed fluid, thus 20 ensuring a very rapid restoration of equal pressures at both sides of the diaphragm.

Furthermore, as may be recognised from Fig. 25 3, the feeding teeth 21 of the one pump 3 are offset with respect to the teeth of the other feeding pump 3. In this Fig. 3 only two toothed 30 wheels with the offset teeth are indicated to give a clear impression, but there can be provided further wheels with correspondingly offset teeth. If only two wheels are used in line or in parallel the setting off of the teeth may be somewhat greater than indicated in Fig. 3, so that the feeding periods are completely equal 35 and that the amount of any possible differences may always be uniform as well.

By means of the plurality of pumps with set-off feeding elements or teeth the stream created and caused to flow to the regulating device will 40 always be as uniform as possible, because there will not arise any interruptions which would be of any practical importance.

Practical trials have shown that even in cases of high counter-pressures no changes in the 45 feeding effect will arise, and certainly this effect is due to the setting of the feeding elements of the plurality of feeding pumps as well as to the symmetrical arrangement of the diaphragm with respect to the feeding and discharge pipes and 50 their openings controlled by the diaphragm.

Having now particularly described and ascertained my said invention what I claim is:

1. Flow quantity regulating system comprising 55 a casing having central inlet and outlet openings in opposite walls thereof, a diaphragm in said casing disposed between said walls, said diaphragm being transversely movable in response to the differential pressure thereon to control the central inlet and the outlet ports, pump means, a conduit between said inlet opening and the intake side of the pump means, a supply conduit for the flow medium connected to said first mentioned conduit, a regulator device in the form of a gear pump, a conduit between the discharge side of the pump means and the inlet side of the regulator, a conduit between the discharge side of the pump means and the inlet side of the diaphragm near its periphery, a conduit between the discharge side of the regulator and the outlet side of the diaphragm near its periphery, and a conduit from the outlet opening, said pump means including a pair of gear wheel pumps the teeth of one pump being out of phase with the teeth of the other pump. 75

2. A device for uniformly delivering a medium comprising pumps, the first of said pumps supplying the medium in excess to the second of said pumps; a diaphragm regulating means; an 5 overflow channel for the quantity in excess arranged between the said pumps which connects to an inlet port of said first pump and the diaphragm regulating means; said diaphragm regulating means comprising a casing, a diaphragm, 10 and inlet and outlet ports provided in the walls of the said diaphragm regulating means, the said inlet port of said means being connected with the said inlet port of said first pump, and the outlet port being connected with the outlet port 15 of said second port, the said overflow channel passing the diaphragm at the inlet port so as to exert pressure on the said diaphragm which is adapted by its deflection under this pressure to control the outlet of the said diaphragm regulating 20 means; and a conduit connected to the said outlet port of said diaphragm means so as to exert pressure on the said diaphragm which is adapted under this pressure by its deflection in the other direction to control the inlet port of 25 said diaphragm means and the said passage way

of the said overflow channel.

3. A flow quantity regulating system comprising a casing having central inlet and outlet openings in opposite walls thereof, a diaphragm in said casing disposed between said walls, said diaphragm being transversely movable in response to the differential pressure thereon to control the central inlet and the outlet ports, pump means, a conduit between said inlet opening and the intake side of the pump means, a supply 10 conduit for the flow medium connected to said first mentioned conduit, a regulator device of lesser capacity than the output of the pump means, a conduit between the discharge side of the pump means and the inlet side of the regulator, 15 a conduit between the discharge side of the pump means and the inlet side of the diaphragm near its periphery, a conduit between the discharge side of the regulator and the outlet side of the diaphragm near its periphery, 20 and a conduit from the outlet opening, said pump means including a gear wheel pump.
